FOLDABLE LOUNGE CHAIR

Marion J. Smith, Columbia City, Ind.

Application April 20, 1954, Serial No. 424,415

6 Claims. (Cl. 155—139)

This invention relates generally to furniture and more particularly is directed to lounge chairs of a type which are primarily adapted for use on lawns, porches and the like.

It is recognized that some lounge chairs are comparatively heavy and cumbersome while others are relatively long and of a permanent rigid character. Chairs of this type are difficult to handle and move about where desired, and cannot be conveniently stored because of their size and bulk.

It is also known that chairs of the knock-down type have not proven entirely satisfactory because in some instances they are comprised of a multitude of components and intricate fasteners or fittings so that it is practically impossible for the average person to assemble the parts without reference to a set of instructions or specifications. Furthermore, the parts do not always fit together properly and this is particularly true after the parts have been put together several times. Moreover, some of the metal fittings, bolts and screws usually employed to operatively connect the major components or parts together are either lost or become too rusty and bent for further use.

With the foregoing in mind, one of the principal objects of the invention is to provide a chair having connected components which can be easily and quickly folded into a compact unit to facilitate handling and storage.

More particularly, an important object of the invention is to provide a durable chair of relatively light weight comprising, among other things, a base frame unit having legs, an arm unit connected to the base for movement from a folded position between the legs to an unfolded operative position for support on the base, track means carried by the arms, and a back and seat pivotally connected together to constitute a unit which is pivotally and slidably connected to the track means. The arm unit is provided with abutments which are respectively cooperable with the back and seat to facilitate adjustment of the latter to any restful position desired by an individual.

A significant object of the invention is to pivotally and slidably connect the back and seat unit to the track means on the arm unit to assist in the adjustment of the unit and at the same time afford an arrangement whereby the back and seat can be folded one upon the other and then swing along with the arm unit so that the arm unit will nest substantially within the confines of the legs of the base and the rest and back unit will nest substantially within the confines of the arm unit to provide a relatively flat sided compact structure of a size substantially within the dimensions of the base frame.

Another object of the invention is to provide an elongated leg rest having wheels at its outer extremity and means for detachably connecting its inner extremity to the base and/or arm unit and/or to the seat, the arrangement being such that the rest can be swung into a nested position substantially within the confines of the base unit

2

and arm unit. With this setup, the rigid base frame unit serves to protect the other units nested therein and offers advantages with respect to storage which will be described subsequently.

5 Another object of the invention is to provide the base with supporting rails for the arm unit and means on the rails and arm unit which cooperate with one another to assist in locating and holding the arm unit in operative position.

10 A further object of the invention is to design and construct the track means and the seat and back unit in such a way that the latter can be readily detachably connected with the track means after the other components of the chair have been assembled.

15 Other objects and advantages of the invention will become apparent after the description hereinafter set forth is considered in conjunction with the drawings annexed hereto.

In the drawings:

Figure 1 is a side view of the chair;

Figure 2 is a top view of the chair;

Figure 3 is a side view of the chair showing the components thereof in a folded or collapsed condition;

Figure 4 is a partial side view in elevation showing the manner in which the leg rest can be attached to the seat;

Figure 5 is a partial sectional view illustrating the way the leg rest is connected to the base of the chair;

Figure 6 is a partial view in elevation depicting one way of locating the arms of the chair in operative relationship with the base;

Figure 7 is a partial sectional view illustrating the connection between the seat and back unit and the track means and the manner in which the arm unit is supported on the base;

Figure 8 is a partial sectional view depicting one form of a connection between the arm unit and the base frame;

Figure 9 is an end view of the chair; and

Figure 10 exemplifies a different way of operatively connecting an arm unit with a base.

Referring first to Figures 1 through 9 of the drawing which exemplify one embodiment of the invention, the chair comprises, among other things, a base frame unit generally designated 1, an arm structure or unit 2 operatively attached to the base by connection means 3, seat structure comprising a seat 4 and a back 5 pivotally connected together to constitute a unit slidable on the arm unit, and a mobile leg or foot rest 6 detachably connected to the base. These units or components may be constructed of any material suitable for the purpose, but are preferably made from tubular and/or flat aluminum stock to make the chair light in weight for convenience in handling, as well as strong and durable.

The base frame 1 may be designed and constructed in various ways but as herein illustrated is generally rectangular in shape and includes a pair of corresponding side rails 7, a front rail 8 forming abutment means, and a rear rail 9. The base also includes a pair of corresponding front legs 10 and a pair of rear legs 11, the latter of which are shorter than the front legs. An axle 12 is carried by the rear legs 11 and supports a pair of wheels 13 to assist in moving the chair where desired. A brace 14 is connected to the front legs 10 and the latter are adapted to engage the ground to assist in holding the chair in place and prevent accidental movement thereof on windy days.

The arm structure or unit 2 may be formed in various ways, but as illustrated in Figures 1 and 2 preferably includes a pair of corresponding curved tubular arms 15 and side rails 16 which are respectively secured to the ends of the arms. The side rails constitute braces or reinforcements for the arms and are formed to provide

track means. A rear cross bar 17 is secured to the arms and constitutes a brace therefor as well as a support for the back 5 and a front cross bar 18 is secured to the fore ends of the arms and serves as a brace and as a support for the seat 4 and leg rest 6.

The seat 4 and back 5, as illustrated in Figures 1 and 2, are pivotally connected together by a cross rod 19 having rollers 20 at its ends for rolling and/or sliding movement within the confines of the track means formed by the side rails 16. As depicted in Figure 7, each of these rails is preferably made in the form of a channel to provide a pair of track formations 21 for each roller. Each rail or channel is open along its inner side to provide clearance for a collar 22 carried by the rod. A collar is located between each of the rollers and the seat so as to center the seat and back unit and space the latter from the track means. It will be noted by referring to Figures 6 and 7 that the bottom of each of the side rails 16 is provided with an entrance opening 23 adjacent its front end so as to facilitate entry of the wheels into the rails or tracks and thereby permit assembly of the seat and back unit with the arm structure after the latter has been completed or made up. In other words, the seat and back unit and the arm unit can be readily detachably connected together.

The seat preferably includes a top portion, depending side walls 24 provided with abutment means in the form of notches 25 and a depending front wall 26 provided with a slot 27, as depicted in Figure 1. The arrangement is such that the seat and back unit can be moved forwardly or rearwardly on the track means to a position desired whereby the back will find support on the rear bar 17 and a pair of opposed notches on the seat will receive and rest on the front bar 18 as shown in Figure 1. If one desires to sit in a more erect position it is merely necessary to shift the unit rearwardly so that the foremost notches on the seat will engage the front bar 18 and when one desires to rest in a reclining position the unit will be moved forwardly so that the rearmost notches will engage the front bar. With this setup the unit can be easily and quickly adjusted, within practicable limits, to meet the needs of any person and when desired, the back can be swung forwardly and upon the seat to protect and keep the seat clean when not in use.

Attention is directed to the fact that when the arm unit is in the operative position shown in Figure 1, the side rails 16 will find support on the side rails 7 of the base so that any strain or weight placed on the side rails 16 is primarily imparted or transferred to the base. This permits one to utilize side rails or track means of a lighter construction.

Attention is also directed to the fact that the front and rear corners of the base are preferably provided with upstanding projections or pins 28, as shown in Figures 3 and 6, which are adapted to snugly fit into the tubular ends of the curved arms 15 whereby to assist in locating and holding the arm unit in position on the base. If found desirable, additional means such as snap-connections or latches may be employed to lock the arm unit in operative position on the base unit.

The arm unit and seat and back unit together constitute an assembly which is detachably and pivotally connected to the base unit as exemplified in the drawing. The connection means 3 for this purpose includes a tubular cross member 29 having its ends extending into and supported on the side rails 16 of the arm structure. As shown in Figure 8, plugs 30 are fixed in the ends of this cross member and screws 31 extend through washers and the rails and threadedly connect with the plugs for detachably securing the cross member to the rails. The connection means also includes a pair of links 32 and 33 having their outer ends respectively rotatably connected to the axle 12 and the cross member 29 and their inner ends are pivotally and detachably connected by a bolt 34. A pair of links 35 and 36, corresponding to the

pair of links 32 and 33, are similarly connected together and to the axle and cross member. In order to impart stability to the connection means, the links are preferably constructed from angle iron and the outer ends of the links are preferably provided with sleeves as shown which surround the axle and cross member. The fact that the cross member is detachably connected to the rails and that the respective pairs of links are detachably connected offer advantages with respect to manufacture and assembly. Attention is directed to the fact that the lengths of respective pairs of links are such that they limit forward movement of the arm unit on the base and thereby assist in locating the ends of the arms in predetermined positions to receive the pins 28. It is to be understood that any means suitable for the purpose, other than the particular form of connection means illustrated, may be employed to establish an operative connection between the arm unit and base.

The leg rest 6 may be utilized in conjunction with the chair and may be made in different ways. As illustrated, the rest includes an elongated top wall 37 having an outer relatively wide extremity 38 to provide a rest for the feet. Except for the wide extremity 38 the rest is made relatively narrow so that it can be easily straddled for convenience in getting into and out of the chair. The leg rest is suitably reenforced by internal web structure as shown and supports a shaft 39. Wheels 40 are carried by the ends of the shaft to promote mobility. The inner extremity of the leg rest, as clearly shown in Figures 4 and 5, is provided with a pair of semi-cylindrical fittings 41 which fit onto the front rail 8 of the base. The inner extremity of the leg rest is further provided with a curved lip or hook portion 42 which rests on the front cross bar 18 of the arm unit as shown in Figure 1. A pair of sliding collars 43 are carried by the front rail and located between the rest and front legs 10 of the base. These collars are urged toward one another by helical springs 44 also carried by the front rail. The collars are recessed as indicated at 45 so as to normally receive the outer ends of the fittings 41 and thereby lock the leg rest to the base unit. To effect a release of the leg rest from the base unit it is merely necessary to slide the collars outwardly until they clear the fittings. Obviously, if found desirable, this particular form of locking means may be eliminated, in which event, the hook 42 on the rest will ordinarily be sufficient to establish an operative connection with the chair. As shown in the drawings, the base unit and arm unit jointly serve as a support for the inner extremity of the leg rest.

When the seat and back unit is moved forwardly to its full limit of travel, the front portion of the seat will extend quite some distance beyond the front of the chair and overlie the leg rest to an extent which renders the rest less serviceable. In order to offset this condition and promote continuity between the seat and rest the hook 42 on the rest can be inserted into the slot 27 in the front wall of the rest as shown in Figure 4.

In view of the foregoing it will be apparent that the seat and back can be placed one against the other and that this unit and the arm unit can be readily swung around and into a nested position substantially within the confines of the base unit as illustrated in Figure 3 and that the leg rest can be swung upwardly and over into nesting relationship with the base unit and arm unit to provide a folded compact assembly. Since this folded chair assembly is more or less flat sided, chairs can be conveniently stacked one upon the other flatwise or edge-wise. This setup allows several chairs of applicant's description to be stored in a much smaller space than is required for a large and long chair of the conventional type.

In the modification of Figure 10 two corresponding pairs of links are provided. The upper links are joined to a tubular cross member 46 extending substantially across the full width of the arm unit. The cross member

is rotatably mounted on a suitable rod and the lower links are joined to a similar cross member 47 carried by a rod. This particular arrangement serves to lend structural stability to the chair and affords a satisfactory way of locating the base unit and arm unit in proper operative relationship.

It will thus be apparent that improved principles of design and construction have been embodied in the chair and that the chair offers many advantages as to use, manufacture and assembly, and storage that are not present in conventional chairs.

Having thus described my invention, it is obvious that various modifications may be made in the same without departing from the spirit of the invention, and, therefore, I do not wish to be understood as limiting myself to the exact forms, constructions, arrangements, and combinations of parts herein shown and described.

I claim:

1. A chair comprising a base provided with legs, an arm unit provided with tracks, a seat and back pivotally connected and movable as a unit on the tracks, and means connecting the arm unit with the base in a manner whereby the seat and back as a unit and the arm unit can be moved from nested positions from between the legs to place the arm unit in a supporting position on the base.

2. A chair of the kind described comprising a base having top rails and legs, an arm unit connected to the base for movement to an operative position on the rails or to an inoperative position below the top rails and between the legs of the base, and seat structure adjustably mounted on the arm unit.

3. The structure defined in claim 2, in which the seat structure is provided with one component of an attaching means, and a leg rest is provided with the other component which is operatively connected to said one component.

4. A chair comprising a base provided with legs, an arm unit provided with tracks, a seat and back pivotally connected and movable as a unit on the tracks, means

25

30

35

40

connecting the arm unit with the base in a manner whereby the seat and back unit and the arm unit can be moved from nested positions from between the legs to place the arm unit in a supporting position on the base, co-operable means on the arm unit, co-operable means on the base, and co-operable means on the seat, and a leg rest provided with means connectible with any one of said co-operable means.

5. A chair of the kind described comprising a base having downwardly divergent front legs and rear legs, an arm unit of a length the same as the distance between the legs at their upper ends, and pairs of links connecting the arm unit to the base for manual movement to an operative position thereon or to an inoperative position substantially between the legs of the base.

6. A chair comprising a base having downwardly divergent front and rear legs, an elongated arm unit mounted on the base, said arm unit being of a length substantially equal to the distance between the upper ends of the legs and provided with track means supporting a seat, and a linkage pivotally connected to the base and pivotally and slidably connected to the track means on the arm unit whereby the arm unit can be swung into a nested position between the legs or on top of the base.
